UNITED STATES PATENT OFFICE.

GEORGE E. BRADBURY, OF CHICAGO, ILLINOIS.

FASTENING.

Application filed June 5, 1925. Serial No. 35,046.

This invention relates to a door fastening or latch and particularly to one which serves to fasten into the closed position a pair of swinging closures. It has for one object to provide a latch which will become automatically effective upon the closing of the doors, so that the doors may be fastened and closed from the outside automatically as they are swung to the closed position. Other objects will appear from time to time throughout the specification and claims.

My invention is illustrated more or less diagrammatically in the accompanying drawings, wherein:

15 Figure 1 is an elevation of the doors and fastener taken from the inside with the parts fastened closed;

Figure 2 is a cross section taken on line 2—2 of Figure 1;

20 Figure 3 is a detailed cross section on an enlarged scale showing the latch bar taken on the line 3—3 of Figure 1;

Figure 4 is a detailed cross section taken on line 4—4 of Figure 1.

25 Like parts are designated by like characters throughout.

A is a door frame with side and top members. It is positioned preferably in a building which is indicated diagrammatically at 30 A¹. A² is the floor of the building.

B is one half of the swinging door. It is hinged to the frame A or to the building A¹. B¹ is a similar swinging door provided on its free edge with a strip B² which overlaps 35 the free edge of the door B when the two are in the closed position. The two doors are mounted so that their lower edges extend slightly below the floor A² of the building.

As shown particularly in Figure 1 the doors 40 when in the closed position abut against the edge of the floor and also as shown against the edge of the frame A. As a result of this construction when they are closed, they rest against these frames and the floor and are held against excessive displacement inward.

45 C is a wedge block fastened to the floor B. It is provided with an outward projection C¹ and an inclined or cam face C². The inclined face is at the upper end of the wedge 50 block.

D is a similar wedge block fastened to the door B¹. It is provided with a projection D¹ and an inclined face D². This position is reversed with respect to that of the wedge 55 block C.

E is a fastening bar pivotally mounted

upon the door B at E¹. It may be swung into the position shown and in that position its ends ride up upon the inclined portions C² D² of the wedge blocks.

F is a latch pivoted to the member F¹ which is secured to the door B¹. G is a metal plate fastened to the fastening bar E at the point where the latter would be contacted by the latch F.

Although I have shown an operative device, still it will be obvious that many changes might be made in size, shape and arrangement of parts without departing materially from the spirit of my invention; and I wish, therefore, that my showing be taken as in a sense diagrammatic.

The use and operation of my invention are as follows:

The invention in the form shown is designed as a garage door, although it is not limited to that purpose. When the garage is to be closed, the door B is moved to the closed position and the fastening bar is swung across into the horizontal position shown. In this position the right hand end of the bar rides up onto the wedge block C and is preferably sprung slightly inward away from the inner face of the door. The door B¹ is then slammed closed. As this is done the left hand end of the fastening bar contacts the wedge block D and is sprung slightly inward away from the door B¹. The latch slips over the fastening bar and engages it, thus holding the doors against outward movement. When the parts are in this position, the doors cannot be opened from the outside.

I claim:

1. As a means for fastening in closed position a pair of closures, a fastening bar movably mounted on one of said closures adapted to extend partially across it and the other, a bar engaging latch mounted on the second closure and adapted when the same is moved into the closed position to engage the bar, and a pair of wedge blocks mounted one on the inside of each of such closures, each adapted to engage one end of the fastening bar when the same is in the fastening position.

2. As a means for fastening in closed position, a pair of closures, a fastening bar pivoted on one of said closures adapted to extend partially across it and the other, a bar engaging latch mounted on the second closure and adapted when the same is in the

closed position to engage the bar, and a pair of wedge blocks mounted one on the inside of each of said closures, each adapted to engage one end of the fastening bar when the same is in the fastening position to bend said end inward away from the inner surface of said closure.

3. As a means for fastening in closed position a pair of closures mounted to swing against an abutment, a fastening bar pivoted on one of said closures, adapted to extend partially across it and the other, means on the second closure to limit its inward movement, said means adapted to contact the first

mentioned closure, a bar engaging latch mounted on the second closure adapted when the same is swung into the closed position automatically to engage the bar, and a pair of wedge blocks mounted one on the inside of each of such closures, each adapted to engage one end of the fastening bar when the same is swung into the fastening position and to bend such end inward away from the inner surface of such closure.

Signed at Chicago, county of Cook and State of Illinois, this 1st day of June, 1925.

GEORGE E. BRADBURY.
